RADIO ANTENNA SYSTEM

Application filed May 22, 1928. Serial No. 279,633.

This invention relates generally to the construction and mode of operation of radio antenna systems, and particularly to antenna systems utilized in radio compass installations.

It is an object of this invention to devise a radio antenna system of the type utilizing a loop antenna associated with a nondirectional antenna, which will be constructed in such a manner that tuning of the loop is substantially unaffected by adjusting the electrical balance between the two branches of the loop.

It is a further object of this invention to devise a radio system particularly suitable for the reception of continuous wave signals, the system making possible a balancing adjustment without substantially affecting the heterodyne or beat note produced in the receiver.

Further objects of the invention will be apparent from the following description in which I have set forth the preferred embodiment of my invention. It is to be understood that the appended claims are to be accorded a range of equivalents consistent with the state of the prior art.

My system may be outlined briefly as comprising a loop antenna, in combination with a nondirectional antenna, both of which antennæ are associated with a suitable signaling circuit. An electrical balancing device is interposed between the nondirectional antenna and the loop, and means is associated with this balancing device whereby it may be adjusted at will without affecting tuning of the loop. The signaling device is preferably of the heterodyne type, as the system is particularly valuable for receiving continuous wave signals. However certain features of my invention are believed broadly new as applied to signaling systems in general.

In the drawing I have illustrated my system as comprising a loop antenna 10, which if the system is to be utilized for taking radio compass observations, is mounted so as to be rotatable about a vertical axis. Associated with this loop antenna there is a suitable signaling circuit 11, principally of the vacuum tube type, as will be presently described.

Tuning of the loop is effected by means of an associated variable reactive element, as for example a variable condenser 12. Coupling between the loop antenna and the signaling circuit 11 is effected preferably by means of an electrically symmetrical arrangement such as is provided by a pair of series connected coils 13, these coils being included in the terminals of the antenna 10 and having variable condenser 12 interposed between the same. Coils 13 are conjointly inductively coupled with coil 14 which is included in the input circuit of signaling circuit 11.

As is customary in radio compass installations, I prefer to divide the antenna 10 into two electrical branches. This may be effected by connecting the midpoint of loop 10 to a point of neutral potential, such as the ground connection 16. It is commonly known that a loop antenna receives signals of maximum intensity along the direction of the plane of the loop, and that signals will be practically of zero intensity when received along a direction at right angles to the plane of the loop. The characteristic curve of such a loop by itself approximates a figure 8, in other words it is bilaterally directional. In actual practice however the theoretical figure 8 characteristic is modified to such an extent as to render such a system inaccurate for direction finders or radio compasses, due principally to the influence of ground currents.

Various electrical means have been employed for securing a perfect balance between the two branches of a loop antenna, thus making possible a closer approximation to the theoretical figure 8 characteristic. In the past such balancing devices have been associated with a loop antenna in such a way as to have a certain effect upon the tuning of the loop. When the system is being employed for comparatively long wave length signals, a slight variation in the tuning of the loop will not affect the reception, but such a variation becomes noticeable and is a distinct detriment when the system is being employed for relatively short wave lengths. Furthermore when receiving signals by the heterodyne method, that is when beating the incoming signals with a local different frequency in

order to produce a differential tone frequency, a change in the tuning of the loop due to adjustments of the balancing device is sufficient to cause a variation in the beat frequency, and such is objectionable and may be confusing to an observer. As has been previously mentioned, in my invention the balancing device is associated with the loop antenna in such a way as to have substantially no effect upon the tuning of the loop.

Referring again to the drawing, I have shown a nondirectional antenna 15 connected to an electrical balancing device 17. I prefer to employ a capacitative balancing device consisting of a central condenser electrode 18 connected to antenna 15 and movable with respect to electrodes 19 and 20. With such a device the respective capacitances afforded by electrodes 19 and 20 with respect to electrode 18, may be varied simultaneously and oppositely by shifting electrode 18. While I prefer to employ a capacitative balancing device, it is understood that inductive or other reactive balancing devices may be employed which utilize two reactive elements capable of opposite and simultaneous variation.

For associating the balancing device 17 with the loop antenna circuit, I have shown a pair of series connected coils 21 connected across electrodes 19 and 20, and both mutually inductively coupled with another coil 22, this latter coil being inserted in series with one of the branches of the loop 10. Coils 21 preferably have the connection between the same connected to a point of neutral potential and for convenience I make both coils 21 of a single continuous winding having its midpoint tapped for the ground connection 23. Coils 21 together with balancing device 17 form a circuit antiresonant to the signals to be received.

In order that the signaling circuit 11 may receive continuous wave signals by the heterodyne method, I have shown an electron relay 26 which is adapted to oscillate at a frequency somewhat different from the incoming signal frequency. Such an arrangement can be afforded by an ordinary oscillating audion relay such as shown. For example I have shown the inductance 14 as being included in the input or grid circuit of electron relay 26, and this inductance is tuned as by means of variable condenser 27. Coil 14 is preferably divided into two electrical sections by ground connection 25. The output or plate circuit of the relay, which is supplied with a suitable source of direct current as by means of the battery 28, also includes an inductance 29 coupled with inductance 14 so as to secure feed back of energy from the output into the input circuit of electron relay 26. The amount of energy fed back may be conveniently controlled as by means of variable condenser 31 inserted in series with

coil 29. A choke 32 has been shown in series with "B" battery 28, in order to prevent bypassing of radio frequency currents.

As is well known such a receiving circuit as described above can be adjusted so as to oscillate locally at a frequency differing from the radio frequency of signals being received. The beat frequency so formed or any other resultant frequency may be detected and then translated, or may be further amplified, detected and then translated. For simplicity I have shown the output of relay 26 as being coupled to a detecting device 33, which supplies a suitable translator 34. In this particular instance the beat frequency is made of an audible tone frequency so as to produce an audible response in the translator 34, this translator being usually the ordinary telephone receivers.

The operation of my system is as follows: The loop antenna is tuned as by means of a variable condenser 12, to the frequency of signals to be received. The signaling circuit 11 is also adjusted so as to receive such signals. If a proper electrical balance does not exist between two branches of loop 10 the characteristics of the system will not be a true figure 8. By adjusting the balancing device 17, however the operator can vary the proportionate amount of energy flowing in the coils 21, and thus the character of the currents induced in coil 22 can be varied. For a certain position of electrode 18 of the balancing device, an exchange of energy will be effected between the two antennæ to balance out disturbing ground currents in the loop antenna. Thus perfect symmetry between the two loop branches can be secured and the system can to an Ewart chain because with this link in a directional characteristic.

Since coils 21 have a fixed relationship with respect to coils 22, it is apparent that adjustment of the balancing device has practically no effect upon tuning of the loop circuit. Thus as far as tuning of the loop is concerned, the balancing device is electrically isolated from the loop antenna. As has been previously explained this result is to be desired, since an operator may then make any necessary adjustments of the balancing device without affecting reception of signals. When the receiving system is arranged for heterodyne reception, as shown and described, there will be practically no variation of the beat frequency as the balancing device 17 is adjusted.

By shifting electrode 18 sufficiently close to one of electrodes 19 and 20, and by employing phase shifting means, the system can be given the characteristics of a cardioid, in which event balancing device 17 can be adjusted to make the cardioid characteristic more perfect. Phase shifting means can be provided by a resistance 36 inserted in the

lead from antenna 15 and normally shunted by a switch 37.

5 My system is particularly useful as a direction finder or radio compass operating on short waves as it makes possible convenient adjustment of the balancing device to secure a sharp minimum response, without making a compensating adjustment of the tuning of the loop.

10 I claim:

15 1. In a radio system, a directional antenna, a non-directional antenna, a signaling circuit cooperably associated with said antennæ, a pair of series connected reactive elements conjointly serving to couple said antennæ, the connection between said elements being connected to a point of neutral potential, a reactive balancing device included in a circuit together with said elements and connected with said non-directional antenna, the arrangement of said elements and said balancing device being such as to render tuning of the directional antenna immune from 20 adjustments of said balancing device.

25 2. In a radio receiving system, a loop antenna, a non-directional antenna, a signaling circuit coupled to said loop, means for tuning said loop, a coil connected in series with said loop, a pair of series connected coils both coupled to said first coil, the connection between said latter coils being connected to a point of neutral potential, and a reactive balancing device having connection with said nondirectional antenna and connected in a circuit 30 which includes said pair of coils.

35 3. In a directional radio system, a tunable circuit comprising a loop, a connection from earth to substantially the midpoint of said loop, an open antenna system, a transformer 40 having a differential primary and a secondary winding disposed in said antenna system and tunable circuit respectively, means to vary the relative magnitudes of current in said primary winding, a signalling circuit, a 45 transformer having primary and secondary windings disposed respectively in said tunable and signalling circuits, and a connection from earth to substantially the midpoint of said secondary.

50 In testimony whereof, I have hereunto set my hand.

GERHARD R. FISHER.
